COMBINATION GARMENT

Hildegard Wipperman, Chicago, Ill., assignor to
 The H. W. Gossard Company, Chicago, Ill., a
 corporation of Delaware

Application March 30, 1934, Serial No. 718,146

1 Claim.

(Cl. 2-30)

This invention relates to combination garments for women and has for its object to provide a light form-fitting garment of this type adapted to give a smooth nonbulging line to the figure and to mold and support the busts with perfect comfort and freedom of movement to the wearer in all positions of the body.

The garment comprises a combined corset and brassière, the latter having an upper front portion constituting individual bust pockets which are shaped to mold and elevate the busts to a high and youthful position, and a lower front portion which telescopes the front of the corset. The brassière is secured to the side edges of the corset and is detached from the corset front, thereby permitting relative up and down movement between the front of the corset and brassière without straining or distorting the busts or impairing the natural symmetry of the garment.

The lower or corset portion of the garment preferably has a stiffened inelastic front section adapted to cover the diaphragm and abdomen to a point adjacent the bustline and means, such as elastic side sections, for fitting the garment snugly about the body and tensioning the front portion across the diaphragm and abdomen. The lower front portion of the brassière may overlap or underlie the front portion of the corset, the extent of the lap in either case being such as to prevent the parts from separating in any position of the body. The sliding movement of the telescoping parts is promoted by the stiffness at the front of the corset and may be further aided by boning or otherwise stiffening the lower telescoping portion of the brassière. The latter expedient is particularly desirable when the lower portion of the brassière underlies the front of the corset.

Another feature of the invention resides in an improved construction of the bust molding portion of the brassière. According to this feature the bust pockets are made of light netting and circular or crescent-shaped inserts composed of firm inelastic material are secured to the inner sides of the bust pockets, forming cups which reinforce the netting and cooperate with the netting to mold and elevate the busts.

These and other features and advantages of the invention will be described in connection with the accompanying drawings, in which:

Figs. 1 and 2 are front and rear plan views of a combination garment embodying the invention;

Figs. 3 and 4 are front and rear views of a model with the garment applied thereto;

Fig. 5 is a front view with the brassière broken open at the front to show its relation to the diaphragm control;

Figs. 6 and 7 are front and rear plan views of a modified combination garment;

Figs. 8 and 9 are front and rear views of a model with this garment applied thereto; and

Fig. 10 is a front view with the corset broken open to show its relation to the brassière.

The combination garment shown in Figs. 1 to 5 comprises a corset having front and rear sections 1 and 2 of inelastic material and longitudinal side elastic sections 3 and 4 extending from the bottom of the garment to about the waistline where they are secured to inelastic side sections 5 and 6, respectively, constituting the sides of the brassière. The side sections or the entire back portion may be made of elastic with either one-way stretch or two-way stretch or a combination of the two, such as, side sections of two-way stretch with the center back section of elastic stretching only up and down, etc.

The entire garment opens at one side and is fastened about the body by cooperating hooks 7 and eyes 8 on the respective meeting edges. An elastic gore 9 is inserted in the lower central portion of front section 1 and a similar smaller gore 10 is inserted in the upper central portion of rear section 2 to provide adjustment. In the garment illustrated, side sections 3 and 4 and gores 9 and 10 are all made of elastic material capable of stretching horizontally but incapable of stretching in a vertical direction. However, these sections can be made, if desired, with stretch in both directions or stretch in one direction greater than in the other, without departing from the spirit or scope of this invention. Garters 12 are attached to the lower edges of the front and rear sections of the garment in any suitable manner.

The front section 1 extends well above the waistline and nearly to the bustline, the upper edge of said section being pointed at the center and sloping down slightly toward the sides in conformity with the general contour of the busts. This section has a central double stay 14 and single side stays 15 and 16 embodied in the lining on the reverse side of the garment. These stays 14 preferably extend to the top of section 1, their purpose being to hold section 1 snugly against the body while furnishing the strength and rigidity necessary to flatten the diaphragm and confine and support the abdomen.

The brassière has an upper bust molding portion made of netting or other soft inelastic material constituting bust pockets 18 and 19 which are shaped to mold and elevate the busts to a conical shape of a very youthful type, these bust 50 pockets being stitched on opposite sides to a lower portion or band 20 made of relatively stiff inelastic material which is shaped at the top to conform to the contour of the busts. The brassière is stitched to the vertical side edges of the corset 55 but is otherwise detached from the corset, and the lower front portion 20 of the brassière overlaps front section 1 for a considerable distance preferably extending about three inches below the upper edge of section 1, permitting portion 60

20 to slide up and down without sliding over the upper edge of section 1 in any normal position of the body. Elastic shoulder straps 21 and 22 are secured to the central upper edges of bust pockets 18 and 19 and have two diverging branches 23 at their opposite ends secured to spaced points on the upper edge of rear section 2, the purpose of these shoulder straps being to hold the busts encased in pockets 18 and 19 in a high and comfortable position at all times.

10 Elastic side sections 3 and 4 mold the hips and tension the stiffened portion 1 of the garment across the diaphragm and abdomen, giving a smooth non-bulging line to the figure and affording a proper foundation for outer garments. The stiffness of front section 1 also affords a smooth slideway for the lower brassière portion or band 20 which is thus permitted to slide freely in accordance with bending movements of the body 15 without straining or distorting the busts from their natural position. In addition, the free up and down motion of the brassière eliminates wrinkles in the material, usual under the bust of an ordinary combination garment, when the 20 wearer is sitting with the body inclined forward or is in other relaxed position.

25 The combination garment of Figs. 6 to 10 comprises a corset having front and rear sections 25 and 26 of inelastic material and longitudinal side 30 elastic sections 27 and 28 which extend from the bottom of the garment and are secured adjacent the waistline to inelastic side sections 29 and 30, respectively, constituting the sides of the brassière. This garment also opens at the side and is 35 fastened about the body by cooperating hooks 31 and eyes 32 as shown in Figs. 6 and 7. Elastic gores 33 and 34 are inserted in the lower central portion of front section 25 and the upper central portion of rear section 26, respectively, to provide 40 adjustment. These gores, as well as side sections 27 and 28, are made of elastic material capable of stretching horizontally but incapable of stretching in a vertical direction. The garters 35 are attached to the lower edges of the front, back and side sections of the garment.

45 Front corset section 25 extends almost to the bustline, the upper edge of said section being pointed at the center and sloping down and then up toward its points of attachment to the sides 50 of the garment in conformity with the general contour of the busts. This section has a central stay 37 and side stays 38 and 49 embodied in the lining on the reverse side of the garment, these stays preferably extending to the top of section 1 55 so as to hold said section snugly against the body while flattening the diaphragm and supporting the abdomen.

60 The brassière has an upper bust molding portion made of light netting which is cut and 65 stitched to form bust pockets 40 and 41 of conical contour. This material is reinforced by annular crescent-shaped inserts 42 which are composed of firm inelastic material and are stitched to the inner sides of the bust pockets with the 70 cut-out portions of the crescents facing the upper edges of the pockets. These inserts give the bust pockets a cupped effect of conical contour, the firmness at the bottom and side edges of the pockets serving to elevate the busts and the elasticity of the netting at the upper and central portions of the pockets serving to gather the material and maintain its conical form. Elastic

shoulder straps 44 and 45 each have two diverging branches 46 secured to spaced points on the upper central edges of the respective bust pockets 40 and 41, adjacent the netting rather than the inelastic inserts 42, and at their opposite ends are 5 provided with similar branches 47 secured to spaced points on the upper edge of rear section 26. These straps provide additional lifting force and serve to hold the busts in a high and youthful position with perfect comfort to the wearer. 10

The brassière also has a lower portion or band 49 of relatively stiff inelastic material which fits the body snugly below the busts. The brassière is stitched to the vertical side edges of the corset with the lower brassière portion or band 49 lying 15 underneath front section 25 of the corset. The brassière front is otherwise detached from the corset and is therefore free to move up and down with respect to the corset as the body bends. Suitable stays 50 are embodied in band 49 on opposite sides of the center to keep the band from wrinkling on the body, and an elastic gore 51 is inserted in the lower edge of said band to hold it tightly against the body while giving sufficient flexibility for comfort in breathing. Band 49 extends down to about the waistline and the central upper edge of corset section 25 extends far enough above said band to prevent the parts from separating in various positions of the body.

20 In both forms of the invention the free up and down movement of the brassière prevents the bust from being drawn down when the body is erect or inclined backward, prevents the formation of unsightly wrinkles below the busts, and give as much comfort and freedom of movement 25 as a two-piece foundation with the smooth lines of a perfect one-piece combination.

20 Various changes may be made in the details of construction herein shown and described without departing from the scope and spirit of the invention as defined by the appended claim.

35 The invention claimed is:

40 A combination garment comprising a corset and a brassière adapted to encircle the body, having an opening at one side extending from top to bottom and fastening means for securing adjacent edges of said opening together, said corset having a stiffened continuous inelastic front portion adapted to cover the diaphragm and abdomen to a point adjacent the bustline and longitudinal side elastic sections for molding the hips and tensioning said front portion across the diaphragm and abdomen, and said brassière having 45 an upper front portion of soft inelastic material constituting individual bust pockets shaped to 50 mold and elevate the busts and a lower front band of stiffer inelastic material secured thereto and extending crosswise and telescoping the front 55 of said corset, said brassière being secured to the side edges of said corset and detached from the front portion thereof permitting the lower front portion of said brassière to move up and down with respect to said corset front without straining or distorting the busts in accordance with 60 bending movements of the body, said longitudinal side elastic sections extending upwardly past the lower overlapping front portion of the brassière and being tapered at their upper ends so as to 65 produce less stretch at the brassière section than at the lower corset section.

70 HILDEGARD WIPPERMAN.
